United States Patent Office.

GEORGE SHARP, OF PHILADELPHIA, PENNSYLVANIA.

Design No. 3,728, dated October 26, 1869.

DESIGN FOR A FORK OR SPOON-HANDLE.

The Schedule referred to in these Letters Patent and making part of the same.

I, GEORGE SHARP, of the city of Philadelphia, in the State of Pennsylvania, have invented and produced a new and original Design for the Handles of Spoons, Forks, Ladles, and similar articles of table use, of which the following is a specification.

The nature of my design is fully represented in the accompanying photographic illustration, to which reference is made, the parts constituting my design consisting of the helmet *a*, shaft *b*, shield *c*, and gauntlets *d*.

Claim.

I claim, as my invention, the design for the handles of spoons, forks, ladles, and similar articles of table use, as shown.

GEORGE SHARP.
